UNITED STATES PATENT OFFICE.

LUCAS B. WILLIAMS, OF HATTIESBURG, MISSISSIPPI.

FIREPLACE CONSTRUCTION.

Application filed May 20, 1922. Serial No. 562,364.

To all whom it may concern:

Be it known that I, LUCAS B. WILLIAMS, a citizen of the United States, and resident of Hattiesburg, in the county of Forrest and State of Mississippi, have invented certain new and useful Improvements in Fireplace Constructions, of which the following is a specification.

My invention relates generally to fire-
10 places, more particularly to open fire places such as are usually installed in dwellings and it consists in the constructions, combinations and arrangements herein described and claimed.

15 An object of my invention is to provide an improved fire place construction affording facilities for regulating the draft thereof to permit of the use of fuels of various descriptions therein.

20 A further object of my invention is to provide a device of the character described which includes means operable at will to convert the device from a closed to an open fire place, or vice versa.

25 Another object of my invention is to provide a device of the character described which is not likely to get out of order easily and which is thoroughly practical commercially.

30 Other objects and advantages will be apparent from the following description, and the novel features of the invention will be particularly outlined in the appended claims.

My invention is illustrated in the accompanying drawings forming a part of this application in which

35 Figure 1 is a front elevation of a fire place embodying the invention in a practical form,

40 Figure 2 is a horizontal section through the embodiment of the invention exhibited in Figure 1 in detached position,

45 Figure 3 is a vertical section through the same embodiment of the invention, and

50 Figure 4 is a vertical section through a fragmentary portion of a modified form of the device.

55 Referring now to the drawings and particularly to Figures 1 to 3 inclusive thereof, the body of the preferred form of the device is made of cast iron or like material cast in a single piece to provide a vertical back 1 having forwardly diverging sides 2-2 extending from the side edges thereof and being connected at their forward edges adjacent to the upper ends thereof by the hori-

zontal portion 3 of a flange having vertical side portions 4-4 extending laterally of the sides 2-2 at the forward edges thereof. The back 1 terminates at its upper end at a level lower than that of the upper ends of the sides 2-2 and the latter are cut away at an acute angle or beveled from the points of their juncture with the back 1 approximately half way to the forward edges thereof, as indicated at 5 in the drawings.

The back 1 is enlarged along its upper edge at 6 and the enlargement is provided with a groove 7 of curved or substantially arcuate cross sectional contour. A horizontal baffle plate 8 is formed integrally with the sides 2-2 and with the flange portion 3 to extend between the sides 2-2 in the plane of the lower edge of the flange portion 3 and from the latter rearwardly to 75 the line at which the sides 2-2 are beveled or cut away at 5. A draft opening 9 is thus provided between the back 1, the sides 2-2 and the rear edge of the horizontal baffle plate 8. The groove provides a seat in which the lower end of a damper plate 10 for controlling the opening or space 9 rests, the damper plate thus being rockingly supported for movement from position to abut at its upper end the rear edge of the baffle plate 8, as 80 shown by the full lines in Figure 3, to the position in which it is disposed in the plane of the back 1 and out of contact with the inclined bevel portions 5 of the sides 2-2 and the rear edge of the baffle plate 8, as 85 indicated by the dotted lines in Figure 3. It will be understood that the dotted lines in Figure 3 show the damper 10 in fully 90 opened position.

A damper operating rod 11 freely slidable 95 in the general direction of its length through an aperture 12 in the horizontal flange portion 3 is pivotally attached at its inner end, as at 13, to an upstanding lug 14 formed integrally with the damper 10 adjacent to the upper end of the latter. The rod 11 is provided with a knob or handle 15 at its outer end which is adapted to be grasped to effect manipulation of the rod to open or close the damper 10, as desired.

100 The sides 2-2 are provided with pairs of integral inward extensions or lugs 16-16 and 17-17 at a desirable distance above the lower ends thereof. The lugs 16-16 and 17-17 lie in the same horizontal plane and the lugs of each pair are provided with opposed seats as indicated at 16a-16a and 110

17^a—17^a respectively, in which are rockingly supported the opposite ends of grate bars 18 and 19 respectively. The distance between the inner ends of the lugs 17, 17 is greater than the distance between the inner ends of the lugs 16, 16 and the grate bar 19 is greater in length than the grate bar 18. The grate bars 18 and 19 have lateral projections extending from opposite sides thereof and upstanding lugs 18^a, 18^a and 19^a, 19^a respectively adjacent to opposite ends thereof, which upstanding lugs extend at right angles to the lateral projections of the bars. Connecting rods 20—20 connect the upstanding lugs 18^a and 19^a at corresponding ends of the grate bars together, being pivotally attached thereto as best seen in Figure 3. The connecting rods 20—20 are rigidly connected together adjacent to their outer ends by means of a transverse bar or rod 21 which has a laterally extending operating portion 22 extending through an opening in a front plate 23 which is supported at its ends upon lugs 24—24 extending inwardly from the sides 2—2 adjacent to the front edges thereof and at spaced distances above the plane of the grate bars. The operating portion 22 is provided with a head 25 at its outer end and is movable substantially in the direction of its length, whereby the grate bars 18 and 19 can be rocked in unison about their respective longitudinal axes.

As stated, the front plate 23 extends above the plane of the grate bars and therefore provides a guard for preventing burning fuel resting upon the grate bars from falling therefrom forwardly thereof. The front plate 23 is provided with a series of apertures 26 through which heat is radiated from the interior of the device into a room in which the device is installed. The space below the grate bars constitutes an ash pit and is normally closed at the front by a removable apertured guard plate 27 which fits between the sides 2—2 and between the lower end of the front plate 23 and the floor. The space between the upper edge of the front plate 23 and the lower edge of the horizontal flange portion 3 and between the vertical flange portions 4—4 can be closed at will by means of a pair of doors 28—28, each provided with upper and lower hinge members 29 and 30 at the outer edge thereof, which hinge members cooperate with hinge lugs 31 and 32 respectively formed integrally with the vertical flange portion 4—4 to extend forwardly thereof, whereby the doors 28—28 are swingingly supported.

From the foregoing description of the various parts of the device, the operation thereof may be readily understood. The device is arranged within an opening in a wall 33 of any suitable known construction in a dwelling or like place and provided with the usual flue or vent (not shown) so that the

opening 9 is in communication the flue or vent of the wall. It will be apparent that when the doors 28—28 are closed, a forced draft through the apertures of the guard 27, upwardly through the grate and through the opening 9 to the flue will be created. The draft can be regulated by operating the damper 10 in the manner described. With the draft regulating means described, almost any known solid fuel can be used in a fire place embodying the invention and a fire therein can be readily started without the use of kindling, inflammable liquid commodities or the like. The front plate 23 and the doors 28—28 serve to guard the clothing of persons approaching the device from the flames therein and at the same time obviate the danger of a fire in a dwelling which might be caused on account of burning coals falling from the grate.

It is important to note that the device heretofore described includes a back as a part of the body thereof, which back is relatively thin and is formed of a metal which is a good conductor of heat. The usual thick layer of brick or other refractory material in a fire place construction between adjacent rooms, one of which is provided with a fire place, may be dispensed with when my device is used and a room adjacent to a room provided with a fire place embodying my invention will thus be heated to a considerable extent by heat radiated from the back 1. A double fire place for heating adjacent rooms in a like degree may be provided by associating with the back 1 in the body of the device identical parts, such as heretofore described as being arranged at one side of the back, at both or opposite sides of the back 1 as illustrated in Figure 4. In the fragmentary portion of the modified form of the device exhibited in Figure 4, the reference characters heretofore used are again used to designate parts at one side of the back 1 identical in essential respects to the corresponding parts heretofore described, and the same reference characters primed are used to designate like parts at the opposite side of the back 1. It is believed that no further description of the construction and operation of the modified form of the device exhibited in Figure 4 is necessary herein or essential to an understanding thereof.

Obviously, my invention is susceptible of embodiment in forms other than those illustrated in the accompanying drawings, and I therefore consider as my own all modifications of the forms of the device disclosed, which fairly fall within the scope of the appended claims.

I claim:

1. In a fire place structure, a body including a vertical back plate and a pair of vertical side plates extending forwardly in di-

verging relation from the side edges of the back plate, said side plates being provided on their inner face with a horizontally spaced pair of alined inwardly extending lugs fashioned at their upper side to provide seats for the ends of removable grate bars, the distance between the inner ends of the lugs of the respective pairs varying with the position of the pairs of lugs in respect to the plane of the front edges of the side plates and the distance between the inner ends of the lugs of the pair proximate to the plane of the front edges of the side plates being greatest.

2. In a fire place structure, a body including a vertical back plate, a pair of vertical side plates extending forwardly in diverging relation from the side edges of the back plate, said side plates having horizontally alined lugs extending inwardly from points

located adjacent to the front edges of the side plates and in a horizontal plane intermediate the upper and lower ends of the side plates, a perforated front plate spanning the front edge portions of the side plates and removably supported at its ends upon said lugs, an apertured guard plate spanning the front edge portions of the side plates and extending below the plane of the lower edge of the front plate to the plane of the lower ends of the side plates, and a pair of doors swingingly supported at the front edges of the side plates for movement to and from position to close the space between the front edge portions of the side plates extending from the plane of the upper edge of the front plate to the plane of the upper ends of the side plates.

LUCAS B. WILLIAMS.
